UNITED STATES PATENT OFFICE.

WILLIAM W. KARSHNER, OF WASHINGTON, DISTRICT OF COLUMBIA.

GALVANIC BATTERY.

SPECIFICATION forming part of Letters Patent No. 280,933, dated July 10, 1883.

Application filed March 23, 1883. (No model.)

To all whom it may concern:

Be it known that I, WILLIAM W. KARSHNER, a citizen of the United States, residing at Washington, in the District of Columbia, 5 have invented certain new and useful Improvements in Galvanic Batteries, of which the following is a specification, reference being had therein to the accompanying drawings.

My invention relates to certain new and 10 useful improvements in galvanic batteries; and the object of my improvements and peculiar construction and arrangement of parts is to construct a galvanic-battery cell that will yield an increased force or strength of 15 current over the common battery now in use, and be so constructed as to permit of the ready removal of any part of said battery when required, and the arrangement of the plates and their connections by which said plates can be 20 removed and replaced at will without being disconnected or disarranged; and, further, my object is to provide means by which sulphate of copper is poured into the jar and carried to the bottom of the same without disarranging 25 any part of the battery.

Heretofore galvanic batteries have been constructed with alternate zinc and copper plates in series, each pair of plates forming a single cell.

30 Referring to the drawings, Figure 1 represents a vertical sectional view of my improved battery, showing the copper at the bottom of the jar and the zinc disks suspended in said jar. Fig. 2 is a detail view, showing the zinc disks separated by metal rings and held in place by a metal rod.

Similar letters refer to similar parts throughout the drawings.

In the drawings, A represents an ordinary 40 glass jar, formed of suitable size and open at the top.

B is the ordinary winged copper plate or plates in the bottom of the jar. c is the insulated copper wire passing from the copper up 45 through the fluid forming the positive electrode. A series of circular zinc disks, D D' D'', are formed of suitable size to permit of sufficient space between the edges of the same and the inside of the jar. Said disks are held 50 at suitable distances apart (from a half-inch to one inch) by metallic thimbles g, preferably formed of block-tin or lead.

C represents a metal rod, formed preferably of brass. Said rod is formed to pass loosely through perforations in the center of the disks D, D', and D''. The inner end of said rod is formed with a head, against which the lower disk, D, rests. Above disk D, surrounding the rod, is placed thimble g. Above thimble g and resting on the end of the same is disk D'. Above disk D' is thimble g', and above said thimble and resting on the same is disk D''. By this construction the number of disk-plates may be increased indefinitely. By this arrangement of the disks I get an increased quantity and intensity of electrical force proportionate to the number of disks used. An adjustable grip-piece, a, has a central perforation, through which rod C passes, and has inserted on each side through screw-threaded 60 perforations set-screws i and i'. Between the brass rod C and the inner end of screw i is inserted the inner end of the conducting-wire b. Said wire is held in contact with the rod C by means of said screw i'. A cross-bar, h, having a central perforation, through which rod C passes, is adapted to rest by its under 65 face on the upper edges of the jar A, and the rod C is held at any desired position within the jar A by means of the grip-piece a and the binding-screw i.

The operation is as follows: The winged copper plate is placed in the bottom of the jar A. The conducting-wire c is attached and carried out over the edge of the jar A. A sufficient amount of sulphate of copper is then placed between the wings of plate B, when a sufficient amount of acid and water is added, then the zinc plates are placed in position and are adjusted to the right position above the copper plate B by means of the cross-bar h, the grip-piece a, and the binding-screw i. The conducting-wire b is then inserted between the end of screw i and the rod C, when, by joining the wires c and b to form the circuit, galvanic action immediately takes place.

One great advantage in this construction of cell over other modes of structure, besides the increase of quantity and intensity of current, is the lively condition in which it keeps itself 90 while on open circuit, with little or no consumption of material, for almost any length of time, and, further, its prompt and continuous action when put on closed circuit, making it 95

equally valuable for telegraph, telephone, and alarm purposes, or electroplating purposes.

For the purpose of feeding in sulphate of copper to keep the battery in full strength, 5 perforations j , j' , and j'' are made in line with each other through plates, or disks D D' D'', and the sulphate of copper is passed to the bottom of the jar A, between the wings of the copper plate B, by means of a tube or funnel.

10 Heretofore the zinc plates in a battery have been suspended in the solution by means of a zinc neck or a zinc rod attached to the plate and usually soldered thereto. The great disadvantage of such a construction is that the acid 15 in the battery solution attacks the zinc neck or rod and eats it off, thus causing the plates to drop down and destroy the action of the battery. The great advantage of a brass or 20 metallic rod used in my invention for suspending said plates is that the acid does not attack said rod, and therefore does not injure it.

Having described my invention, what I claim and desire to secure by Letters Patent is—

25 1. A galvanic battery consisting of a jar

containing sulphate of copper and water, a winged copper plate resting on the bottom of said jar, within said solution, a conducting-wire having its inner end secured to said plate, as shown, and a series of perforated circular 30 zinc plates separated by thimbles and suspended in the battery solution by a solid metallic rod held in place by a cross-bar and screw-nuts, said screw-nuts connecting to said rod one end of a conducting-wire, substantially as shown and specified. 35

2. The combination of the jar A, holding sulphate of copper, acid, and water, the copper plate B, and the wire c, with the disks D D' D'', thimbles g and g', rod C, having head f, 40 cross-bar h, grip-piece a, thumb-screws i and i', and wire b, substantially as shown and specified.

In testimony whereof I affix my signature in presence of two witnesses.

WILLIAM W. KARSHNER.
